SIGN CHARACTER

George W. Frost, Springfield, Ill., assignor to
 Gothard Manufacturing Company, Springfield,
 Ill., a corporation of Illinois

Application January 14, 1939, Serial No. 250,954

4 Claims. (Cl. 40—140)

My invention relates generally to reflecting signs and it has particular relation to individually mountable reflecting sign characters made legible at night to occupants of passing automobiles by reflection of light from the head lights thereof.

An important object of my invention is to prevent destruction of the reflecting surface of reflecting sign characters due to expansion and contraction of adhesive material with change in temperature.

Another object of my invention is to provide individually mountable reflecting sign characters in which the reflecting material comprises substantially straight strips easily obtainable in such form.

Another object of my invention is to provide individually mountable sign characters in which the mirrored surface of the reflecting material used therewith is not susceptible to rapid deterioration when the sign characters are mounted in the open.

Another object of my invention is to provide individually mountable sign characters which are easily repaired if it becomes necessary to do so.

Still another object of my invention is to provide a simple and economic method of constructing and assembling individually mountable reflecting sign characters.

Other objects of my invention will, in part, be obvious and in part appear hereinafter.

It is to be understood that the expression "sign characters" used hereinafter in the description and appended claims is intended to cover any letter, numeral, figure, pattern, or symbol that may be used to make up reflecting signs. Characters used on traffic signs such as arrows, curves, S-curves, and crosses are all within the scope of this expression.

Accordingly, my invention is disclosed in the embodiment hereof shown in the accompanying drawing, and it comprises the features of construction, combination of elements, and arrangement of parts which will be exemplified in the construction hereinafter set forth, and the scope of the application of which will be indicated in the appended claims.

For a more complete understanding of the nature and scope of my invention, reference may be had to the following detailed description, taken in connection with the accompanying drawing, in which:

Figure 1 is a plan view of the front of a reflecting sign letter "O" constructed according to my invention, and representative of any desired sign character;

Figure 2 is a view in vertical section taken on line 2—2 of Figure 1;

Figure 3 is a plan view of the back of the letter "O" shown in Figure 1;

Figure 4 is an end view of the letter "O" shown in Figure 3 before the lugs have been turned over to complete the assembly of the letter; and

Figure 5 is a sectional view taken on line 5—5 of Figure 4 showing in detail the assemblage 5 of the mounting screws.

Referring now particularly to Figures 1 and 2 of the drawing, the reference character 10 designates generally a reflecting sign letter "O" constructed according to my invention. The sign 10 character 10 comprises a channel-shaped member 11 in the channel of which reflecting material 12 is deposited with rim flange sections 13 and 14 fitting over the channel-shaped member 11 to retain the reflecting material 12. The rim 15 flange sections 13 and 14 comprise flanges 15 and rims 16. By having the flanges 15 extend over the outer edges of the reflecting material 12, the reflecting material 12 will be securely held in place. 20

The reflecting material 12 may be in the form of substantially straight strips A and B. The strips A and B substantially fill the channel recess of the channel-shaped member 11. If desired, suitable plastic material may be forced 25 around the edges of the strips A and B between the sides thereof and the inner edges of the channel-shaped member 11 and also between adjoining pieces or strips A and B. Such plastic material will prevent any movement of the strips 30 A and B and prevent any great quantity of moisture gathering behind the reflecting material 12 which might on freezing break it up. However, when the channel-shaped member 11 and the strips A and B are made with reasonable accuracy, very little or none at all of the plastic material will be needed. 35

Although various types of reflecting material 12 may be used, I have found that one known as "Diffusex Glass" gives excellent results. Such 40 "Diffusex Glass" has been used in the reflecting sign character 10 as indicated at 12 and it comprises a layer of glass 17, the outer surface 18 of which is roughened to impart a diffusing effect thereto and the rear or back of which is provided 45 with a reflecting film or coating 19. The film 19 may be formed by spraying molten aluminum onto the back of the layer of glass 17 which is heated to a temperature just below its fusion point. "Diffusex Glass" made with such a mirrored surface of aluminum 19 is not susceptible 50 of rapid deterioration when used in the open or outdoors.

Referring now to Figures 3 and 4 of the drawing, it will be noted that the rims 16 of the rim 55 flange sections 13 and 14 are provided with tabs 25. When the rim flange sections 13 and 14 are in place over the channel-shaped section 11, as shown in Figures 1 and 2 of the drawing, these tabs 25 may be spun or otherwise turned over 60

onto the back of the channel-shaped member 11 to hold the rim flange sections 13 and 14 and the channel-shaped member 11 together. If it becomes necessary to subsequently take the respecting sign character 10 apart, the tabs 25 may be turned up or back to allow the sign character 10 to be repaired. In Figure 4 of the drawing, the tabs 25 are shown in upright position before being spun or turned over.

10 In order that the reflecting sign character 10 may be readily mounted, mounting screws 30 may be provided as shown in Figures 3 and 5 of the drawing. The back of the channel-shaped member 11 may be offset in a number of places as indicated at 31 and apertures 32 provided therein through which the mounting screws 30 may be inserted. The heads 33 of the screws 30 are preferably countersunk and edges of the apertures 32 are spun over as indicated at 34 to retain the screws 30 in place.

20 With a view to increasing the conspicuousness of the reflecting sign character 10 in the daytime, the faces of the flanges 15 of the rim flange sections 13 and 14 may be colored. For example, 25 black enamel may be baked on the flanges 15 before the rim flange sections 13 and 14 are assembled with the channel-shaped member 11. By having the rim flange sections 13 and 14 separably mountable, it is possible to bake the 30 enamel on the flanges 15 before the complete assemblage of the reflecting sign character 10. If the flanges 15 had to be in place over the reflecting material 12 and enamel subsequently baked thereon, such baking would spoil the reflecting 35 character of the reflecting material 12.

From an assemblage standpoint there is great advantage in having a channel-shaped member 11 of the general outline of the desired sign character for holding strips or pieces of the reflecting material 12 in place during the assembly of the sign character 10.

40 For example, it would be difficult from an assemblage standpoint to hold the piece of reflecting material 12 in proper position on a flat backing plate and then place retaining means thereover. Only a relatively small number of different lengths and shaped pieces or strips of reflecting material 12 are needed from which almost any sign character can be made up. Thus it is 45 not necessary to have especially provided pieces of the reflecting material 12 for each different sign character desired as would be the case if the sign character could not be built up from separate pieces. For instance, in making up a 50 numeral 6 or 9 three strips such as A in Figure 1 and one strip such as B, could be used, it being necessary to provide only two additional strips of different lengths to complete such numerals. There is great advantage in using straight strips 55 of reflecting material 12. Such strips may be easily cut from a relatively large plate of reflecting material 12. Whereas, it is very difficult to cut out from such a large plate the complete outline of the desired character and, in addition, cutting out a complete outline gives a 60 large amount of waste reflecting material.

The channel-shaped back member 11 and the rim flange sections 13 and 14 may be cast aluminum or other metal. Such castings are cheaply made in quantity and require very little finishing. Molded plastic material such as "Bakelite" 65 may also be used if desired.

70 Since certain changes may be made in the above construction and different embodiments

of the invention may be made without departing from the scope thereof, it is intended that all matter contained in the above description and shown in the accompanying drawing shall be interpreted as illustrative and not in a limiting 5 sense.

I claim as my invention:

1. An individually mountable reflecting character comprising, in combination, a metal channel-shaped member, light reflecting material disposed in the channel thereof, integral metal rim flange retaining means fitting around and over the edges of said channel-shaped member to retain said light reflecting material in place, tabs integrally formed on the rear of said rim flange 10 retaining means being overturned onto the back of said channel-shaped member to thereby hold said rim flange retaining means and said channel-shaped member together and mounting screws held on the back of said channel-shaped 15 member for mounting said mountable reflecting character, said channel-shaped member, light reflecting material, and rim flange means all conforming to the general outline of said sign 20 character.

2. A reflecting sign character comprising, in combination, a channel-shaped member, light reflecting material disposed in the channel of said channel-shaped member, and rim flange retaining means cooperating with said channel-shaped 30 member to retain said reflecting material therein, said channel-shaped member, light reflecting material, and rim flange retaining means all conforming to the general outline of said sign character, and the outer surface of the flange of said 35 rim flange retaining means being colored to increase the legibility of said sign character in daylight, said light reflecting material comprising glass one surface of which is light diffusing and the opposite surface of which is mirrored 40 with aluminum.

3. A reflecting sign character comprising, in combination, channel-shaped means, light reflecting material disposed in the channel of said channel-shaped means, and rim flange retaining 45 means cooperating with said channel-shaped means to retain said reflecting material therein, said channel-shaped means, light reflecting material, and rim flange retaining means all conforming to the general outline of said sign character, said light reflecting material comprising substantially straight pieces of light reflecting material, and the flange part of said rim flange retaining means covering only the outer edges of said light reflecting material and having an 50 area sufficiently large to make the reflecting device visible in daytime.

4. A reflecting sign character comprising, in combination, a channel-shaped member, light reflecting material disposed in the channel of said 60 channel-shaped member, and rim flange retaining means cooperating with said channel-shaped member to retain said light reflecting material therein, said channel-shaped member, light reflecting material, and rim flange retaining means all conforming to the general outline of said reflecting sign character, and the outer surface of the flange of said rim flange retaining means being colored to increase the visibility of said sign character in daylight, said light reflecting material comprising glass, one surface of which is light diffusing and the opposite surface of which is mirrored. 65

GEORGE W. FROST.
